US00D790122S

(12) **United States Design Patent** (10) **Patent No.:** **US D790,122 S**
(45) **Date of Patent:** **** Jun. 20, 2017**

(54) **ELECTRONIC VAPING DEVICE**

(71) Applicants: **Eric Hawes**, Richmond, VA (US); **Traci Martin**, Richmond, VA (US); **Melissa Burroughs**, Richmond, VA (US); **Berina Yerkic-Husejnovic**, Richmond, VA (US); **Raymond Lau**, Richmond, VA (US); **Christopher S. Tucker**, Midlothian, VA (US); **Anthony Dibitonto**, Richmond, VA (US); **Marc Sauriol**, Richmond, VA (US); **George Stafford**, Richmond, VA (US); **Jamie Nicholson**, Richmond, VA (US); **Mark Breneman**, Richmond, VA (US); **Alistair Bramley**, Richmond, VA (US)

(72) Inventors: **Eric Hawes**, Richmond, VA (US); **Traci Martin**, Richmond, VA (US); **Melissa Burroughs**, Richmond, VA (US); **Berina Yerkic-Husejnovic**, Richmond, VA (US); **Raymond Lau**, Richmond, VA (US); **Christopher S. Tucker**, Midlothian, VA (US); **Anthony Dibitonto**, Richmond, VA (US); **Marc Sauriol**, Richmond, VA (US); **George Stafford**, Richmond, VA (US); **Jamie Nicholson**, Richmond, VA (US); **Mark Breneman**, Richmond, VA (US); **Alistair Bramley**, Richmond, VA (US)

(73) Assignee: **Altria Client Services LLC**, Richmond, VA (US)

(**) Term: **15 Years**

(21) Appl. No.: **29/545,534**

(22) Filed: **Nov. 13, 2015**

(51) LOC (10) Cl. **27-01**
